UNITED STATES PATENT OFFICE

171,503

EARRING OR THE LIKE

Adolph Katz, Providence, R. I., assignor to Coro,
Inc., New York, N. Y., a corporation of New York

Application September 29, 1953, Serial No. 26,995

Term of patent 7 years

(Cl. D45—9)

To all whom it may concern:

Be it known that I, Adolph Katz, a citizen of the United States of America, residing in Providence, county of Providence, and State of Rhode Island, have invented a new, original, and ornamental Design for an Earring or the like, of which the following is a specification, reference being had to the accompanying drawing, forming part thereof.

Fig. 1 is a plan view of an earring or the like, showing my new design.

Fig. 2 is an edge view thereof.

I claim:

The ornamental design for an earring or the like, substantially as shown.

ADOLPH KATZ.
